UNITED STATES PATENT OFFICE.

JAMES WARD PACKARD, OF NEW YORK, N. Y.

MERCURY AIR-PUMP.

SPECIFICATION forming part of Letters Patent No. 401,581, dated April 16, 1889.

Application filed May 19, 1888. Serial No. 274,437. (No model.)

To all whom it may concern:

Be it known that I, JAMES WARD PACKARD, a citizen of the United States, residing at New York, in the county of New York and State 5 of New York, have invented certain new and useful Improvements in Mercury Air-Pumps; and I do hereby declare the following to be a full, clear, and exact description of the invention, such as will enable others skilled in the 10 art to which it appertains to make and use the same.

The object of my invention is the production of a combination of mercury trap and valve for air-pumps which shall be absolutely 15 impervious to the passage of air and at the same time be free from the liability to breakage characteristic of the ordinary apparatus.

In the drawings, Figure 1 represents a well-known form of mercury-pump with my invention attached. Fig. 2 is a vertical section showing on an enlarged scale my invention. Fig. 3 is a detail view of the siphon, the line of sight being in the direction of the arrow in Fig. 2.

25 In the drawings, P represents the mercury-pump, well known in the art, having the vacuum-bulb G' and the mercury-bulb G. The lamp L is attached for the purpose of exhausting the air from the bulb. The upper 30 portion or neck of the pump is all made in one piece and sealed on to the vacuum-bulb G'. Within the chamber M, Fig. 2, is the siphon S, having the upright portion E and the inverted portion E'. The space C within the 35 chamber M is filled with mercury nearly to the level of the bend between the portions E and E' of the siphon. Within the chamber N, above the siphon-chamber, is placed the floating glass valve V. Between the chamber 40 N and the chamber M the neck of the pump is drawn in, so as to form a valve-seat, W, for the valve V.

The operation of the pump is in the well-known way. The mechanical air-pumps connected by means of the pieces of hose shown 45 in Fig. 1 are operated in such manner as to force the mercury from the bulb G into the vacuum-bulb G'. As the mercury rises, it forces all the air above it up to the siphon S. 50 The air bubbles up through the mercury in

the space C and escapes under the valve V. When the action of the mechanical pumps is reversed, the mercury is withdrawn from the vacuum-bulb G', the valve V comes down upon its seat W, and the mercury in the 55 chamber M prevents any small quantity of air which may slip under the valve V from passing on to the vacuum-bulb G'. Thus a complete vacuum is left within the bulb G', and the moment the mercury sinks below the 60 connection of the bulb G' with the lamp L an equilibrium of pressure results, and a great quantity of the air remaining within the lamp-bulb L is removed. A sufficient number of repetitions of this operation produces a nearly 65 complete vacuum in the lamp-bulb L.

I am aware that a siphon sealed with mercury in the manner I have described, and for the purpose of forming an air-tight trap, is 70 not new in the art; but in practice the use of this device alone has been found inoperative, for the reason that the great pressure upon the mercury in the trap would drive a little of it back through the siphon at each operation, and soon it would be entirely exhausted and 75 the pump cease to work. On the other hand, the use of the valve made in the ordinary way has been attended with difficulties, in that it was liable to breakage when suddenly lifted by the upflowing mercury, and also in 80 that no matter how carefully it was ground and fitted to its seat there was more or less leakage, which, of course, interfered with the highest efficiency of the pump.

By combining the siphon and the valve and 85 in making the whole in one continuous piece with the vacuum-bulb G', I have attained in practice a complete air-check, which is absolutely impervious to the passage of air and which works with its highest efficiency for an 90 indefinite period of time. The mercury-trap and the siphon furnish the features of imperviousness, while the valve above them prevents the forcing of the mercury through the siphon and the consequent disabling of the 95 pump. In addition, there is little danger of the valve V being lifted so violently as to break it, and the sealing of the neck of the pump containing my invention directly onto the vacuum-bulb leaves no joints for leakage. 100

Having therefore described my invention both in essence and detail, what I claim as new, and desire to protect by Letters Patent, is—

- 5 1. In a mercury-pump, the combination of the siphon-chamber, the siphon in said chamber sealed by a quantity of mercury, a valve-chamber above the siphon-chamber, and a floating valve seated within said valve-chamber, substantially as described.
- 10 2. In a mercury-pump, the combination, with the valve-chamber, a valve seated in said

chamber, the siphon-chamber below said valve-chamber, the siphon within the siphon-chamber, and the vacuum-bulb below the siphon, the valve-chamber, siphon-chamber, siphon, and vacuum-bulb all made in one piece, substantially as described. 15

In testimony whereof I affix my signature in presence of two witnesses.

JAMES WARD PACKARD.
